SAIL RIGGING

Fred C. Schwanke, Chicago, and Edmund J. Sheehan, Wilmette, Ill.; said Sheehan assignor to Watson D. Harbaugh, Evanston, Ill.

Filed Apr. 20, 1960, Ser. No. 23,453

18 Claims. (Cl. 114—91)

This invention relates to rigging sailboats particularly yachts and sailboats of the racing type having weighted keels.

In the design of sailboats, consideration is given to the relative fore and aft locations of the keel area and the sail areas under average wind speed and wave action conditions expected in the area where the boat will be sailed. The positions are determined to extract the maximum effort from the winds at the average expected or prevailing wind speed with the least amount of drag exerted by the rudder in holding the boat on a course. In brief, the boat should hold its course with no helm when the sails are properly set under prevailing wind conditions.

Although the invention improves the operation and performance of multi-mast sailboats, for purposes of further discussion and description the invention will be described as embodied in a single mast sloop-rigged sailboat of the 22 square meter class where the hull design is somewhat open while the sail area is fixed.

Such a sailboat when the hull is designed for prevailing wind and wave conditions will tend to luff or go to wind when the wind speed is above the optimum for which the boat was designed is not held back by use of the continuous use of the rudder. This is experienced when the wind direction is ahead of the beam and particularly on a beat when the boat is as high into the wind as possible without luffing and with the boat remaining properly heeled as indicative of the fact that wind is exerting a forward effort upon the sails and the keel is continuing to exert a lateral pressure upon the water. As conventionally known the result of these pressures is a forward movement of the boat generally referred to as headway. However, any correction exerted by the rudder constitutes a drag in the water which slows the boat.

In winds lighter than the optimum wind speed for which the boat is designed, the boat will tend to fall off or turn with the wind. Here again, correction must be applied at the helm and the rudder action slows the boat.

Essentially speaking, with these circumstances and factors in mind, the design of the boat is related to the amount of heel that is to be experienced with the boat under average wind speeds and a given sail area limitation. At this heel, the hull will be in contact with the water on its longest running or "racing" line thereby affording least possible resistance of the water against displacement within the hull speed to which the boat is designed. The more the heel the more to windward, the less the heel the more to leeward will be the tendency of the boat to sail.

The closer the boat can point into the wind the shorter the distance to the next mark, the closer to its racing line the boat can be heeled the greater the speed, and the less helm required to hold the boat on its point, the quicker the mark is reached. Herein lie three essential competitive advantages in sailboat racing and design. The present invention is provided to capitalize on all three as well as upon the first and third if desired alone.

One of the objects of the present invention is to provide in a single boat the advantages of both heavy weather and light weather designs in that with a given sail area such may be moved fore and aft from an initially optimum position with respect to the keel to capitalize on the first and third advantages above mentioned.

2

A further object of the invention is to keep the boat as near to its longest running line as possible under all wind conditions to capitalize on the second advantage above mentioned, it being appreciated that it is the effective effort of the wind pressure on the sail area exposed to it that determines the heel of the boat.

Another object of the invention is to increase the effective area of a sail presented to the wind under light wind conditions and to decrease the effective area of the sail to bring the boat to its longest running or racing line under heavy wind conditions.

Another object of the invention is to maintain a controlled heel relationship between the sailboat and the water surface at all times to minimize the amount of frictional contact and water displacement drag within the hull speed factor.

A further object of the invention is to provide an improved mechanism to adjust the angular relationship between the mast and the deck of the sailing vessel through 360° of the compass.

Another object of the invention is to provide an improved fore and aft rigging adjustment for a sailboat mast whereby a greater efficiency may be obtained from the wind by changing the center of pressure of the sail relative to the center of pressure of the keel when wind conditions change.

A further object is to rig the sail fore and aft without slack on any stays yet with a balanced load on the adjustment and with a self locking adjustment mechanism requiring little work effort to operate.

Another object of the present invention is to provide an improved lateral adjustment for the rigging of the mast whereby the angular relationship of the mast relative to the deck of the sailing vessel may be changed.

A further object of the invention is to provide means for rigging the mast to port or starboard with a self locating adjustment mechanism which automatically changes the mast when the boat comes about in heavy wind without any slack on the shrouds or stays.

A further object of the invention is to provide an improved shroud control for varying wind conditions.

A still further object of the invention is to provide an improved jib sail adjustment coordinated with a fore and aft mast rigging adjustment for altering the position of the jib sail as the angular relationship of the mast is changed relative to the surfaces of the deck of the sailing vessel.

A further object of the invention is to provide an improved take-up adjustment mechanism for maintaining a constant tension on the mast through the fore and aft stays.

A still further object of the invention is to provide an improved take-up adjustment to maintain a constant tension on the mast through the port and starboard shrouds.

A still further object of the invention is to provide improved adjustments which are simple in construction and capable of manual operation to correct for wind changes that affect the balance of a sailing vessel.

With the foregoing and other objects in view, the invention resides in the following specification and appended claims, certain embodiments and details of construction of which are illustrated in the accompanying drawings, in which:

FIG. 1 is a view in side elevation of the sailing vessel to which the invention is applied;

FIG. 2 is a fragmentary view in front elevation illustrating the rigging for the upper portion of the mast;

FIG. 3 is a section view taken along line 3—3 of FIG. 1 showing a preferred embodiment of the shroud control for the lateral adjustment of the mast and shrouds;

FIG. 4 is a fragmentary cut-away view in plan elevation showing the adjustments of this invention;

FIG. 5 is a fragmentary cut-away view in side elevation illustrating the adjustments of this invention;

FIG. 6 is a side elevation view showing the wind-up drum for the lateral adjustment;

FIG. 7 is a plan view similar to FIG. 4 showing a simplified control embodiment for fore and aft rigging of the mast separately or for tilting the mast laterally in operation with the embodiment shown in FIG. 3 for tilting the mast laterally; and

FIG. 8 is an enlarged view of a portion of FIG. 7.

Referring now particularly to the drawings, the sloop rigged sailing boat indicated generally by the numeral 1 has an upright mast 2, a depending weighted keel member 3 and a deck 4. The mast 2 rests on the deck 4 on a ball and socket fitting 7 and held erect by fore and aft shrouds 10 and 11 on both sides and fore and aft stays 15 and 16 respectively. The mast supporting fitting in turn is braced from the bottom of the hull 9 by a strut 5 at the chain plates 6 which shape the boat amidship.

The ball and socket fitting provides a pivotal mounting for positioning the butt of the mast adjustably fore and aft of the boat when rigging and tuning the sails initially. The details of construction of the ball and socket fitting are not shown because they are conventional and once set merely serves as a fixed pivot point for the bottom of the mast and allows the top of the mast 2 to be positioned in an infinite number of positions within the range of the rigging adjustment mechanism herein explained. The optimum position of all parts can be determined when the boat is "tuned" and this will be assumed to be the condition of the boat for purposes of describing the invention and its operation.

Referring now specifically to FIGS. 2 and 3, a plurality of sheaves 8 are rotatably mounted to the chain plates 6 below and next to the gunwales 9g. The shrouds 10 and 11 are secured to the upper portion of mast 2 at one end at vertically spaced points as shown in FIG. 2 including a spreader member 14 and pass down through the openings 12 and 13 in the deck 4. Below the deck 4, the shroud members 10 and 11 pass around the sheaves 8 and can be, if desired, secured directly to a worm drive adjustment as shown in FIGS. 4 or 7, or as shown in FIG. 3 they may be tied together through a hydraulically driven piston arrangement which will be further described later, it being appreciated that for simplicity of description only one shroud on each side of the boat need be mentioned except where otherwise indicated.

As mentioned, the mast is rigged fore and aft by stays 15 and 16, respectively, same being secured to the uppermost portion of the mast and passing downwardly through the deck 4. The fore stay 15 may be one or two in number and are sometimes called jib stays after passing through the deck 4, attaches to an equalizer adjustment linkage 17. Extending from the jib adjustment linkage 17 is a stay haul 18 which passes around the sheave members 20 which are secured to the bottom of the hull 9. The stay haul 18 extends to the center portion of the sailing vessel and terminates on a cam surface adjustment mechanism 25 wherein a tightening of the stay haul 18 draws the top of the mast forwardly, and, a slackening of the stay haul permits the mast to move aft.

A jib down haul (FIG. 5) is shown at 21 and extends downwardly from the tack clew 21a through the deck 4. Below the deck 4 the down haul 21 passes around a pulley 22 which is secured to the equalizing linkage 17 and terminates on a tensioning mechanism 23 which is used each time a jib is set.

The jib down haul mechanism 23 comprises a worm 23w threaded through a female threaded member 23s of a threaded drive joint which permits the worm to follow the shave 22 up and down. The worm is operated by a crank handle member 33. It is seen that upon actuation of the adjustment 24, that the fore stay and linkage 17 will be re-positioned by the action of the stay haul 18.

Also, it will be seen that equalization of tension between the forestay and the jib down haul is accomplished by the equalization linkage 17. Thus, with the turning of the handle or crank 33 the top of the mast 2 is moved fore or aft without varying the proportional tensions on the stays unless desired and that the worm 23w and nut 23s is a self locking arrangement against self-rotation when the handle 33 is released, it being appreciated that the jib down haul mechanism as shown in FIG. 5 permits the equalizing linkage 17 to move up and down about the support on the nut 23s of the worm 23w.

The back stay 16 in like manner, passes downwardly through the deck 4 at a point 20 and passes around a plurality of sheaves 19, some of which are not shown in the drawings, and terminates on a cam adjustment mechanism 25 which will now be described.

The fore and aft adjustment 24 of the mast is best seen in FIGS. 4, 5 and 7, and includes a dual cam arm lever 25 pivoting about a point 26. A short radius cam 25a has the ends of the shrouds 10 and 11 secured thereto through an equalizer 10c. A wider radius cam 27 has the fore stay haul 18 attached thereto and a much wider radius cam 28 has the back stay attached thereto. Also shown in FIG. 7 are the running back stays 30s which are controlled by releasable winches 30w when coming about and these stays pass through blocks 30b which are secured to back stay hauls 30h which are fastened to a cam 30c on the lever 25.

Secured to the cam arm lever 25 at 29, is a threaded actuating worm 30 which extends toward the rear of the boat where it receives a nut or runner means 31 mounted in a suitable header. A handle or crank member 32 actuates the worm and by it the lever 25.

By way of explaining the various cam radii it is readily seen that the angles between the rigging members and the deck are different. The angle made by the back stay 16 with the deck 4 is more acute than the angle made by the running back stay 30s and the shroud angle is greater yet. The fore stay 15 angle with the deck 4 is also different. Furthermore the rigging members are of different lengths. Therefore, it becomes necessary, if a balanced tension is to be maintained in the fore and aft rigging elements, that a different and proportioned cam radius and contour be supplied for the adjustment mechanism. Illustrated in FIG. 4, the movement of the dual cam arm lever 25, by means of the crank 32 and through the action of the cam surfaces 27 and 28, will either position the uppermost portion of the mast fore or aft with the mast pivoting in the pivotal mounting 7 depending on what direction the handle 32 is rotated and the tensions on the rigging members will remain constant.

Moreover, it will be observed that there is no load on the lever 25 and pivot 26 except the work load performed by the sail under wind pressure. Under high wind pressure the lever wants to go in the direction it should to move the mast forward so there is little load on the handle 32 for this purpose, and when the mast is to be moved aft, the wind pressure is generally light. Thus, the adjustment effort provided is light under most conditions. Even under heavy wind on a beat, the worm is strong enough to move mast easily into the wind.

Referring now specifically to FIGS. 3, 4 and 6, two forms of lateral adjustment of the mast 2 are shown as made through a lateral adjustment mechanism supported by the hull 9. In FIGS. 4 and 5 it is mounted on the lever 25.

This comprises in FIG. 4, winches 25w and 25x having worm wheels 25t disposed in load balancing engagement with a worm shaft 33a propelled by a handle 35. The winches of course turn oppositely but the shrouds 11 are wrapped around the winch 25w in one direction and the running back stay hauls 30s are wrapped around the winch 25x in the opposite direction. The axis of rotation of the respective winches corresponds to the

5

radii mentioned in connection with FIG. 7 and their respective diameters are determined to follow lateral movement of the mast without changing tensions during the change.

Referring now to FIG. 3 a hydraulic pump 36 operating a piston 37 in a cylinder 38 is employed. The mechanism 34 is mounted on a cross bracket 39 bracing the chain plates 6 at the sheaves 8.

The mechanism 34 comprises in addition to the piston and cylinder, two piston rods 40 extending outwardly in sealed relationship through opposite cylinder heads 41. The two rods move as a unit and their outermost ends are secured to the ends of the shrouds 10 and 11 so that as the piston 37 is moved one way or the other hydraulically the shrouds shift the top of the mast 2 in the opposite direction.

The piston is powered through a hand pump 42 also having a double ended piston 43 so that two people can operate it, one pushing and one pulling on the power stroke if necessary. The output of the pump is valved through a selector valve 44 to deliver hydraulic fluid under pressure to one side of the piston 37 or the other. Thus, by operation of the pump, the shrouds and the mast can be moved either to port or starboard, which relationship is primarily useful in light weather since the mast must be moved towards the wind, if, on a particular tack at the time, the change is desired, otherwise the mast can be moved with the wind.

The two ends of the cylinder are connected by a bypass 45 which includes an adjustable bleed valve 46. Whenever it is decided by the skipper that he will bring the boat about, in light weather the bleed valve 46 is opened just before coming about and the wind pressure moves the mast to the desired side of the boat by the fluid being bled to the other side of the piston 37 as the piston moves with the mast. The valve 46 is closed and the boat is brought about, with the mast then rigged towards the windward side of the boat.

At this time it might be well to indicate that in heavy weather the mast is moved to leeward and the valve can be left open enough to permit the wind pressure to accomplish this with the cylinder 38 then serving as a dash pot controlled by the valve as the boat tacks.

Both relationships involve the desire to heel the boat to but not beyond its best running or racing line.

Means is provided for positively bringing the mast back to center or upright position as well limiting the lateral movement thereof, and, although the full effort for this could be borne by the hydraulic pump, nevertheless in order to be safe in event the hydraulic system failed or it was only desirable to use it as a dash pot system, two stop members 50 are slidably mounted on the cross brace 39 and oppositely threaded at 51 to receive a shaft 52 threaded at one end with a right hand helix and at the other end with a left hand helix as at 53. The shaft is rotated by the worm wheel 35b as driven from the worm shaft 35a. Thus, a double worm reduction drive assures power enough to right the mast under all conditions and the stops 50, threads 53 and shaft 52 operate as a turnbuckle to drive the stops towards or away from each other.

The ends of the shrouds, or the piston rods, if desired, are provided with stops 51a and these stops cooperate with the adjustable stops 50 to limit the lateral movement of the mast equally on opposite sides of center, these limits being variable as adjusted by the worm drive. Full movement of the stops 50 towards each other brings the stops 51a and the piston 37 to center position and holds the mast in its center position until they are again moved outwardly. Moreover, with the valve 46 closed, the mast can still be held thereby in center position while the stops 50 are separated and made ready and then when the valve is released, the mast will move outwardly under wind pressure to right the boat to more nearly its racing line heel.

6

Although there is little change in the effective length of the shrouds with fore and aft movement of the mast, it will be appreciated that shortening and lengthening the shrouds may be accomplished between one or both of the sheaves 8 and stops 50 by tightener pulleys such as shown at 60 and these are carried by levers 61 connected by shroud hauls 62 fastened to the lever 25 as shown in FIG. 7 according to the principles of different radii and cams as already described. This prevents the stops 50 from relieving the balancing load exerted by the shrouds on the lever 25.

In this connection, although the running back stay haul 30h could be connected to the piston 37 through same motion proportioning means such as a lever, it is not necessary to do this since the running back stays are set each time the boat is brought about.

By the two adjustments, the lateral mast adjustment and the longitudinal mast adjustment, it is possible to position the mast in an infinite number of attitudes relative to the deck surface 4. Thus, it becomes evident that upon a change of the wind in velocity or in direction, it is quite easy to take immediate corrective measures to keep the boat in trim by re-positioning the pressure center of the said to trim anew and maintain the maximum work effort of the sails and the heeling of the hull to its racing line. As is easily understood that mast is thus moved forward to counteract any tendencies of the boat to luff in heavy wind and is moved aft to hold the boat into the wind in light winds. The adjustments are made by the skipper until the boat will hold its course without any helm and the racing line is attained for the hull.

Likewise, it is quite obvious that the mast may be tilted to the starboard or the port, depending upon the direction of the wind, to establish the hull as near to its racing line as possible, whereby the gunwales or other attachments on the vessel will not come into contact with the water, thus causing an increased friction and hence reducing the speed of the vessel.

It will be readily apparent to those skilled in the art how the present invention provides an improved and useful adjustable rigging for shifting the mast and attains the objects stated. It will also be seen how it is adaptable for use on any size sailing vessel including multi-masted boats with the masts interlocked for joint operation, and how various and further changes can be made without departing from the spirit of the invention, the scope of which is commensurate with the appended claims.

We claim:

1. In a sailboat having an upright mast movable fore and aft at its top, the combination of a back stay, a jib stay and a jib down haul, strain equalizing means between said jib stay and jib down haul, means for tightening the jib down haul, and means interconnecting the back stay and strain equalizing means including a lever transmitting the strain on the back stay to the equalizing means and means connected to the lever for moving the lever to shift the top of the mast fore and aft through concurrent movement of the stays by the lever.
2. The invention as set forth in claim 1 wherein the strain equalizing means and the back stay are connected at radially spaced points on the lever with the back stay connection of the greater radius.
3. The combination called for in claim 1 including shrouds passing through the deck aft the bottom of the mast, and means connecting said shrouds to said lever near the fulcrum of the lever for movement in the same direction as the back stay.
4. A rigging for sailboats comprising a mast, fore and aft stays for the mast and shrouds for the mast, adjustment means interconnecting the fore and aft stays of the rigging and means interconnecting the shroud rigging, said adjustment means being pivotally mounted and having multiple cams of different radii engaging said stays and shrouds in supported relationship to maintain constant

resting tensions thereon, said fore stay rigging pulling against the aft stay and shroud rigging through said adjustment means, said cams of different radii being so constructed and arranged that the pulls of the stays and shrouds thereon substantially balance out in said adjusting means.

5. A sailboat having a keel and a sail carrying mast extending upwardly from the deck surface comprising, means pivotally mounting the bottom of the mast on the sailboat, rigging means secured to the upper portion of the mast including a fore stay, back stay and lateral shrouds, first adjustment means secured to said rigging means for angularly adjusting the mast in a longitudinal direction relative to the boat to change the pressure center of the sail with respect to the keel, and second adjustment means secured to the shrouds to angularly adjust the mast in a lateral direction relative to the boat to change the effective sail area of the sail exposed to the wind.

6. The invention as set forth in claim 5 wherein the sailboat has a deck and the pivotal mounting means for the mast is adjustably movable fore and aft on the deck.

7. Mast rigging for sailboats comprising fore and aft rigging, first adjustment means supported on the boat and interconnecting the fore and aft rigging, port and starboard rigging, second adjustment means supported on the boat and interconnecting the port and starboard rigging, said first adjustment means having multiple cam surfaces maintaining constant tension on the fore and aft rigging, and said second adjustment means including a single contoured surface maintaining constant, balanced tension between the port and starboard rigging, means for operating said two adjusting means concurrently to change the relative position of the pressure center of the sail with respect to the boat.

8. The invention as set forth in claim 7 wherein said first adjusting means includes a pivoted arm member and the multiple cam surfaces thereon are of different contour.

9. The invention as set forth in claim 7 wherein said first adjusting means includes a pivoted arm member supporting said multiple cam surfaces of different contours and said second adjusting means includes a contoured spool on said pivoted arm member.

10. The invention as set forth in claim 7 wherein the support of both adjusting means are on a common axis and the surfaces of both of said adjustment means are disposed on the same side of said axis with all of the rigging aft the mast opposing all the rigging afore the mast to maintain constant tension in the rigging means.

11. A sailboat having a pivotal mast extending in an upward direction and secured by adjustable rigging com- 50

prising, pivotal mounting means for the mast, first adjustment means secured to the rigging for angularly positioning the mast in a longitudinal direction relative to the boat, hydraulic adjustment means secured to the rigging for angularly positioning the mast in a lateral direction relative to the boat, and third adjustment means co-ordinated with said hydraulic adjustment means for limiting lateral movement of the mast and thereby control the change of the center of pressure of the sail relative to the boat.

12. The invention as set forth in claim 11 wherein said pivotal mounting means is adjustable for moving the bottom of the mast fore and aft.

13. The invention as set forth in claim 11 wherein said first adjustment means includes a pivotal arm member having a pair of contoured cams of different radii.

14. The invention set forth in claim 11 wherein said hydraulic adjustment means includes a piston and a bleed valve by-pass controlling the rate of movement of the piston for controlling the rate of lateral adjustment of the mast.

15. The invention as set forth in claim 11 whereby said hydraulic adjustment means includes an idler member co-ordinating said first adjustment means therewith.

16. The invention set forth in claim 11 wherein said first and hydraulic adjustment means interconnect portions of said rigging means and maintain constant tension in the whole of the rigging means.

17. The invention according to claim 5 wherein said first adjustment means is a pair of contoured cams of different radii secured to a pivotal arm member, and said second adjustment means is a winch carried on said pivotal arm member.

18. The invention as set forth in claim 11 wherein said first adjustment means includes a pivotally mounted arm member having a plurality of contoured elements of different radii, and said third adjustment means includes a floating link member coordinated with said first adjustment means to control lateral movement of the mast.
